CLAIM

I claim the ornamental design for a display cabinet for coins, as shown and described.

DESCRIPTION

FIG. 1 is a perspective view of one embodiment of a display cabinet for coins, the display cabinet having five drawers; FIG. 2 is a front elevation view of the display cabinet of FIG. 1;

FIG. 3 is a rear elevation view of the display cabinet of FIG. 1;

FIG. 4 is a top view the display cabinet of FIG. 1; FIG. 5 is a bottom view of the display cabinet of FIG. 1; FIG. 6 is a side elevation view of the display cabinet of FIG. 1;

FIG. 7 is a perspective view of one embodiment of a display cabinet for coins, the display cabinet having eight drawers; FIG. 8 is a front elevation view of the display cabinet of FIG. 7;

FIG. 9 is a rear elevation view of the display cabinet of FIG. 7;

FIG. 10 is a top view the display cabinet of FIG. 7; FIG. 11 is a bottom view of the display cabinet of FIG. 7; and,

FIG. 12 is a side elevation view of the display cabinet of FIG. 7.

The features of the display cabinet shown in broken lines are for illustrative purposes only and form no part of the claimed design.

1 Claim, 8 Drawing Sheets
